UNITED STATES PATENT OFFICE.

THOMAS J. CRUMP, OF BUENA VISTA, TEXAS.

HAME-FASTENER.

SPECIFICATION forming part of Letters Patent No. 240,666, dated April 26, 1881.

Application filed October 9, 1880. (No model.)

To all whom it may concern:

Be it known that I, THOS. J. CRUMP, a citizen of the United States, resident at Buena Vista, in the county of Shelby and State of Texas, have invented certain new and useful Improvements in Hame-Fasteners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 represents a front view of this invention. Fig. 2 is a side view, and Figs. 3 and 4 are details.

This invention relates to devices for fastening the ends of hames; and it consists in the 20 construction herein specified.

In the drawings hereto annexed, A is a curved rack-bar, having a loop, a, at one end. Sliding upon this bar is a clasp, C, having a loop, B, corresponding to loop a, and upon the same 25 side of rack-bar A. Upon the rack side of bar A clasp C is provided with a pinion, E, engaging said rack.

To one side of clasp C there is affixed a slotted cylinder, C'. Projecting through this cylinder is the operating-post F of pinion E. This 30 post F is slotted, and at the end of this slot

there is a pin, g, which enters a slot, g', in a locking-plate, G, which said plate, by its slot-connection with post F, can be thrown into and out of the slot in said post, being held 35 therein by pin g.

The loop or hook a is attached to one hame-loop and B to that of another hame.

The plate G is slid out of the slot in cylinder C', and by using plate G as a handle the 40 clasp C is moved along rack-bar A, pinion E traveling over the rack until the hames are brought in the desired position, when plate G is thrown into the slot again and the device is held fast.

45 To loosen the hames it is only necessary to reverse the operation.

Having described my invention, what is claimed, and for which Letters Patent are sought, is—

50 In a hame-fastener, the combination of rack-bar A, having hook a, with the clasp C, having hook B and slotted cylinder C', and pinion E, having post F and slotted locking-plate G.

55 In testimony whereof I affix my signature in presence of two witnesses.

THOS. JEFFERSON CRUMP.
